United States Patent Office.

JOSEPH MILLER, OF CUBA, NEW YORK.

Letters Patent No. 61,553, dated January 29, 1867.

IMPROVED CAR-COUPLING.

The Schedule referred to in these Letters Patent and making part of the same.

TO ALL WHOM IT MAY CONCERN:

Be it known that I, JOSEPH MILLER, of Cuba, in the county of Alleghany, and State of New York, have invented a new and improved Car-Coupling; and I do hereby declare that the following is a full, clear, and exact description thereof, reference being had to the accompanying drawings, making a part of this specification, in which—

- Figure 1 is a front view of one of the couplings applied to a passenger car.
- Figure 2 is a vertical sectional view, taken longitudinally through the coupling, of fig. 1.
- Figure 3 is a front view of one of the couplings adapted for a freight car.
- Figure 4 is a longitudinal section, taken vertically through the coupling of fig. 3.
- Figure 5 is a top view of the draw-heads connected together.
- Figure 6 is a perspective view of one of the hooked draw-heads.
- Figure 7 is a perspective view of a draw-head with a common link coupling attached to it.
- Similar letters of reference indicate corresponding parts in the several figures.

This invention relates to certain novel improvements on that class of railroad car-couplings in which the coupling of two cars is effected by the means of hooks, which are so constructed as to couple of themselves, when the cars are forcibly brought together, by interlocking with each other.

The nature of my invention consists mainly in the employment of hooks in pairs, applied to flanged draw-heads, which are so arranged as to be capable of receiving an oscillating movement about their axes; said hooks being made so as to interlock right and left, and to allow of the passing around curves without becoming disconnected or twisted; said hooks being also adapted for having attached to them coupling links, so that any car with the hooked couplings can be connected to the cars with the common link and pin-couplings, all as will be hereinafter described.

The invention also consists in providing a simple and efficient means for adjusting a rocking hooked coupling, higher or lower, as circumstances may require, and at the same time providing for the use of elastic pressure and draw-springs at the rear ends of the draw-rods, for relieving cars from shocks and injury in stopping and starting a train, as will be hereinafter described.

To enable others skilled in the art to understand my invention, I will describe its construction and operation.

In the accompanying drawings, figs. 1 and 2 represent my improved coupling applied to the end of a passenger car so as to be conveniently operated by a brakeman upon the platform. The coupling-head A is applied on the projecting end of a cylindrical draw-bar, B, which is made of a suitable length, and terminated at its inner end in a short stud, a, which receives upon it a metallic or rubber spring, b. This spring is confined in place between two collars, c c, on the stud a. The spring b and collars c c are enclosed within a strongbox, C, which is bolted to the flooring timbers D in any suitable manner, so that endwise play of the draw-bar is allowed by the compression of the spring b; and all shocks and concussions are received by this spring, and a corresponding one applied to the draw-bar on the opposite car. The front part of the draw-bar B is supported by means of a stirrup, C¹, which is bolted to the bottom side of the front platform beam, as shown in fig. 2, and which is made of sufficient length to allow of all the vertical play required of the front end of said draw-bar. This stirrup C¹ not only serves to support the draw-bar, but it also serves to sustain it against lateral displacement. To adjust the front end of the draw-bar to different heights, a notched wedge, E, inserted laterally through the stirrup C¹ beneath the bar B, may be employed, or, if desirable, a vertical screw may be used, inserted through the bottom of the stirrup, so as to support upon its end the said draw-bar. If the notched wedge E is used for adjusting the draw-head vertically, it may be moved by means of a lever, or otherwise. For freight or box cars, the plan represented in figs. 3 and 4 for raising and lowering the draw-head or front end of the draw-bar. This plan consists in suspending the front part of the draw-bar B by means of a sliding stirrup, C², which is placed astride of the transverse beam D', and constructed so as to receive through its lower ends said draw-bar, as shown in fig. 4. A stirrup, C¹, is also employed for guiding the bar B and sustaining it against lateral displacement, as described for the plan illustrated in figs. 1 and 2. Through the upper end of the sliding stirrup C², a wedge, F, passes transversely, which wedge is supported by and moved upon the transverse beam D' by means of the rod e. This rod is bent or cranked on each side or end of the wedge F, and its extremities are also bent, as shown in fig. 3. By turning the rod e, which passes freely through the wedge F, so that its

ent ends are perpendicular to the end of the car, the wedge may be moved endwise so as to raise or lower the draw-head or front end of its bar. By rod e back to its former position, its cranked portions will be caught by the pin i , and the wedge will be prevented from moving out of place. By means of the rod e the wedge F may be adjusted by a person standing at either side of the car without going between two cars. A collar or band, h , encircles the draw-bar in rear of its forward supporting stirrup, and to this collar a lever-arm, h' is secured. A tenon, which is formed on the collar h , enters a longitudinal slot which is made in said draw-bar, so that, by vibrating arm h' , the draw-bar and its head will receive a rocking movement. The attachment of the collar h by means of its tenon and groove will allow of a free independent endwise movement of the draw-bar. In passenger cars the draw-bar B is rotated or oscillated by means of a lever, G , which is pivoted to the front of the car platform, as shown in fig. 1. The lower end of this lever, G , is connected to the arm h' by means of a rod, G' , and spring, j . The upper end of lever G is held in the desired position by means of notches, k k' k'' , in the guard rail H . For freight cars, a draw-rod, I , which is held in place against the end of the car body, is used in conjunction with a spring, j' , for vibrating lever h' , which in this case projects upward from its draw-bar B . The rod I has two notches in its lower edge, which are used for holding this rod and the draw-bar in the desired positions.

I will now proceed to describe the construction of the draw-heads or coupling heads A , which are suitably secured upon the projecting ends of the draw-bars, as shown in the drawings. The draw-heads A are constructed exactly alike, with segmental hooked portions, m m , projecting from their circular ends, so that when two draw-heads are brought together the hooked surfaces will interlock with each other. Each head has two hooked segments formed on it, and arranged diametrically opposite each other, with a central space between them. These quarter segments are constructed to hook in opposite directions, and the hooks are arranged nearly in the same line, so that when two heads are coupled together they will allow of a lateral vibration for turning curves in the road. To prevent the uncoupling of the hooks by the lateral shaking motion of cars while in motion, I construct flanges, n , on each end of the circular heads, as shown in figs. 3, 5, 6, and 7, which form lateral stays for the ends of the hooks when coupled together. The side faces p p of the hooks m m are bevelled, as shown in the drawings, so that when two cars are brought together the bevelled surfaces on the hooks of one head, A , impinge upon the corresponding surfaces of the hooks on the opposite head A , and cause the heads to move about their axes a sufficient distance to allow the hooks to interlock. The hooks on the draw-heads are held in position for coupling by means of the springs, upon the levers or rods, which are used to oscillate said heads, as above explained, so that when two heads are forcibly brought together they will interlock of themselves, and the hooks will be held together by the force of the springs, as aforesaid. The hooks of each head A are perforated at rr for the purpose of receiving through them a coupling pin L for connecting a common coupling link, L' to the heads, as shown in fig. 7. The pin holes and projections m must be brought in a vertical line to receive said pin and link, for which purpose the rod or lever which is used to oscillate the heads is moved into the proper position, and held by its notch, as described. This feature of my invention is a very important one, as it admits of the coupling of cars having the common link couplings with cars having my improved oscillating hooked couplings.

It will be seen from the above description of my invention that I employ self-locking coupling hooks which are adapted for being connected to the common link couplings, and which are formed on flanged heads that prevent casual uncoupling of cars; said hooks and heads being formed on or applied to adjustable rocking draw-bars, which are allowed to have an elastic endwise play for relieving shocks and concussions, and which are provided with means by which these rods and their heads can be readily uncoupled without subjecting the brakemen to danger of being crushed between cars. In casting the heads and hooks I shall chill those surfaces which are subject to wear, so as to harden and render them durable.

Having described my invention, what I claim as new, and desire to secure by Letters Patent, is—

1. Draw-heads A , with interlocking hooks m m , and flanges n , substantially as described.
2. The oscillating or turning hooked draw-heads A , which are adapted for having connected to them the common coupling links, substantially as described.
3. Interlocking or hooked turning and sliding draw-bars, constructed and operating substantially on the principle herein set forth.
4. An adjustable stirrup C' , in combination with the sliding wedge F and adjusting rod e , substantially as and for the purposes described.
5. The lever or rod connected to the lever-arm h' , which latter is secured to a collar h , through which the draw-bars have an endwise movement, substantially as described.
6. The combination of a spring j with the devices which are employed for oscillating or turning the draw-head and its bar; said spring being so applied as to act upon the draw-heads to keep the hooks thereof together, substantially as explained.
7. The combination of the turning and sliding draw-bars, with spring b b , substantially as and for the purposes described.

JOSEPH MILLER.
